[57] CLAIM

The ornamental design for a battery housing, as shown and described.

DESCRIPTION

FIG. 1 is an isometric view of a battery housing showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof; and,

FIG. 7 is a left side elevation view.

The broken line showing in FIGS. 1, 3 and 4 is included for the purpose of illustrating features or structure of the battery only and forms no part of the claimed design.
